UNITED STATES PATENT OFFICE.

WILLIAM MILLER, OF ST. LOUIS, MISSOURI, ASSIGNOR TO STANDARD RAILWAY EQUIPMENT COMPANY, OF EAST ST. LOUIS, ILLINOIS, A CORPORATION OF ILLINOIS.

CARLINE.

1,029,570

Specification of Letters Patent. Patented June 11, 1912.

Application filed February 26, 1912. Serial No. 679,881.

To all whom it may concern:

Be it known that I, WILLIAM MILLER, a citizen of the United States, and a resident of the city of St. Louis and State of Missouri, have invented a new and useful Improvement in Carlines, of which the following is a specification.

This invention relates to carlines for freight car roofs.

10 It has for its principal objects to produce a structure which will resist racking movement of the roof, hold the upper portion of the car body square and prevent one side plate from moving ahead of the other; and 15 to attain certain other advantages herein-after more fully appearing.

The invention consists in the parts and in the arrangements and combinations of parts hereinafter described and claimed.

20 In the accompanying drawings which form part of this specification and wherein like symbols refer to like parts wherever they occur, Figure 1 is a fragmentary view showing the portion of a carline adjacent 25 to a side plate in side elevation, the side plate being shown in section; Fig. 2 is a top plan view of the parts shown in Fig. 1; Fig. 3 is a fragmentary perspective view 30 of the end portion of the channel member detached; Fig. 4 is a perspective view of the saddle and gusset plate; Fig. 5 is a side elevation of the entire carline connecting the two side plates; Fig. 6 is a view similar to Fig. 1 showing a modification of the 35 structure; Fig. 7 is a top plan view of the parts shown in Fig. 6; Fig. 8 is a fragmentary perspective view of the channel member of the modification; and Fig. 9 is a perspective view of the saddle and gusset 40 plate.

Referring now more particularly to the construction shown in Figs. 1 to 5, inclusive, the carline comprises a metal channel member or body 1 extending continuously from 45 side plate A to side plate A of the car, the flanges of the channel being disposed upwardly. The end portions 2 of the web of the channel are turned down, and thereby 50 adapted to be secured to the inner faces of the side plates of the car by bolts 3.

At each end of the channel 1, a metal gusset plate 4 is riveted thereto, the gusset plate being below and resting flatwise against the web of the channel. The inner 55 end of each gusset plate is wider than the

channel and has its marginal portions turned upwardly outside of and alongside of the flanges of the channel, the gusset plate and the channel being secured by rivets extending through said upturned portion of the 60 gusset plate and the corresponding flange of the channel. The sides of the gusset plate diverge from the inner end toward the outer end, the outer end being considerably wider than the inner end and extending longitudinally as well as laterally beyond the ends of the channel or body member of the carline. The projecting end portion of the 65 gusset plate is bent upwardly, then horizontally, and then downwardly so as to form a saddle adapted to fit over the side plate of the car. An opening 8 is provided at the middle of the saddle portion to permit the insertion therethrough of the downturned portion 2 of the channel. The saddle 70 portion of the gusset plate is provided with downturned portions 9 at its inner side which are secured to the inner face of the side plate by bolts 10. A wooden filler 11 is placed in the channel member and is secured 75 thereto by bolts 12. This wooden filler extends from side plate to side plate.

In the construction illustrated in Figs. 6 to 9, the channel member 1^a is shown arranged with its web horizontal and its side flanges extending downwardly. The end portion of the web of the channel member is slotted longitudinally for a considerable distance and the two severed portions 13 are spread apart so that the ends of the member become substantially Y-shaped. The ends of the portions 13 are turned downward, as at 14, and secured to the inner face of the side plate of the car by bolts 15. The gusset plate 16 in this construction is substantially like that illustrated in Fig. 4 except that its flanged marginal portions 17 extend downwardly. These marginal portions 17 are secured to the flanges of the channel member back of its spread ends, or bifurcated portions, by rivets 18. The bifurcated portions of the channel member are secured to the under side of the gusset plates by rivets 19. The gusset plate is provided at the middle of its inner side with a downturned portion 20 which is secured to the inner face of the side plate by a bolt 21. In lieu of the wooden filler, purlins 22 are secured to the top of the carline by bolts 23.

From the foregoing description, it will be

seen that by reason of the side plates being directly connected by the channel member or body of the carline, and the gusset plate being riveted to the channel member and 5 provided with a relatively wide saddle portion straddling the side plate, the roof structure is materially stiffened.

Obviously, the device admits of considerable modification without departing from 10 my invention. Therefore, I do not wish to be limited to the specific construction and arrangement shown.

What I claim is:

1. A sectional carline comprising a 15 flanged body member having bifurcated ends adapted to be secured to the side plates of a car and separate end members secured flatwise to said bifurcated ends respectively, each end member consisting of a wide- 20 spreading gusset plate having a saddle portion adapted to fit over the side plate of the car.

2. A metal carline comprising a channel member spread at the ends, and gusset plates 25 secured flatwise against the outer surface of the respective spread ends of said channel member, and having marginal flanges embracing the flanges of said channel member back of the spread of the ends thereof, each 30 of said gusset plates widening toward the end of said channel member and having a saddle portion adapted to fit over the adjacent side plate of the car.

3. A metal carline comprising a channel 35 member whose web extends horizontally, the end portions of the web of said channel

being bent downward, and a gusset plate secured flatwise to the web portion of said channel member near its ends, the side marginal portions of said gusset plates adjacent 40 to the inner ends of said gusset plates being flanged and secured to the flanges of said channel member, said gusset plates widening toward the ends of said channel member and having saddle portions adapted to fit over 45 the side plates of the car and downturned portions adapted to be secured to the inner faces of said side plates.

4. A metal carline comprising a channel member whose flanges extend vertically, the 50 end portions of said channel member being slotted longitudinally and the severed portions spread apart, the ends of said severed portions being turned downward, and a gusset plate secured to the web portion of said 55 channel member near the slits, the side marginal portions of said gusset plate adjacent to their inner ends being flanged and secured to the flanges of said channel member, said gusset plates widening toward the 60 ends of said channel members and having saddle portions adapted to fit over the side plates and downturned portions adapted to be secured to the inner faces of said side plates. 65

Signed at St. Louis, Missouri, this 28th day of February, 1912.

WILLIAM MILLER.
